VENTILATING ATTACHMENT FOR
WINDOWS

Charles Raw, Toledo, Ohio

Application June 21, 1933, Serial No. 676,891

2 Claims. (Cl. 98—99)

This invention relates to a ventilating attachment intended particularly for use in connection with vertically swinging windows of the type commonly used in attics and basements, and has for its object the provision of a simple and efficient means of this character, which is capable of being easily and quickly applied or removed, and which maintains the window in partially open or outwardly swung position to permit ventilation or circulation of air in the associated chamber, and which at the same time effectually prevents blowing in of snow, rain, or the like.

The invention is fully described in the following specification, and while it is capable of embodiment in numerous forms, one embodiment thereof is illustrated in the accompanying drawing, in which—

Figure 1 is a vertical section of a window and casing, with the window swung partly open and equipped with a ventilating attachment embodying the invention; Fig. 2 is a front elevation thereof; Fig. 3 is a section on the line 3—3 in Fig. 2; Fig. 4 is a perspective elevation of one of the side plates of the attachment, and Fig. 5 is a perspective view of a screen adapted to be used in connection with the attachment.

Referring to the drawing, 1 designates a window casing of the type commonly used in attics or basements, 2 the window sash hung at its top within the casing for vertical swinging opening and closing movements, and 3 a jamb strip provided within the casing and against which the window sash closes, as is common with windows of this type. A side protecting plate 4 is mounted in upright position in each side portion of the casing 1 with its rear vertical edge in abutment with the respective side of the casing jamb 3 and with its forward edge inclined to correspond to a particular incline of the inner surface of the window sash when the window is swung outward into partially open position as shown, so that the outer upright edge of the plate may have substantially parallel engagement with the sash.

The rear or jamb engaging edge of each plate 4 is flanged outwardly and then rearwardly in L-form, as shown at 5, to seat against the jamb, and at the same time have its edge projecting into a recess 5a therein, as shown in Fig. 3.

The forward or sash-engaging edge of each plate is doubled back upon itself, as shown at 6, and has lengthwise sliding interlocking engagement with a supplemental holding strip 7 attached to the sash. The lower end of each plate rests on the sill 8 of the window casing, having an end surface 9 conforming to the slope

of the sill for such purpose, and from a point near the outer edge of the sill, preferably has its lower end inclined outward and upward to the point of engagement with the window sash, as shown at 10. Each plate is of such height 60 that the upper end of the forward inclined sash-engaging side thereof terminates within the outer side edge of the window casing.

The plates 4 are easily and quickly applied to a window by simply swinging the window to outward 65 open position sufficient to permit the turned over edge 6 of each plate to be slid into interlocking engagement with the respective retaining strips 7, after which the window sash, with the plates attached, is swung inward until the rear edges 70 of the plates seat against the jamb 3 in interengagement with the recess 5a. Hooks 11 attached to the sides of the jamb 3 are then engaged to eyes 12 provided on the plates, such eyes, in the present instance, being shown as formed by 75 tongues pressed inward from the respective plates. These hooks prevent both the plates and window sash from swinging outward.

A screen 13 may be provided between the lower edge of the window sash and the forward edge 80 portion of the sill 8 in coaction with the lower inclined edges 10 of the plates, so as to cooperate with the plates 4 to effectually screen and protect the associated room from the outside. The screen 13 may have its outer edge inserted in a recess 85 14 provided along the inner side of the lower portion of the sash.

It is apparent that when the window 2 is in open position and the protecting plates 4 attached thereto, the casing opening will be effect- 90 95 properly protected against rain and snow blowing therein from the sides and at the same time a sufficient opening will be left between the lower edge of the window sash and casing sill to permit proper ventilation.

I wish it understood that my invention is not limited to any specific arrangement or form of the parts, as it is capable of modifications and changes without departing from the spirit of the claims.

Having thus described my invention, what I claim as new, and desire to secure by United States Letters Patent, is:

1. The combination with a window casing and a vertically swinging window sash hung therein, 105 of a protecting plate disposed in each side of the casing opening with its rear edge in abutment with the casing at the respective side of the opening and with its outer edge doubled over and parallel with the inner side of the window sash 110

when in predetermined open position, means attached to the inner side of the sash at each side of the casing opening and having sliding interengaging connection with the doubled over edge 5 of the respective plate, and means for attaching the plates to the casing.

2. The combination with a window casing having a jamb with the sides thereof vertically recessed in their forward faces and a vertically 10 swinging window sash hung in the casing, of a protecting plate in each side of the window casing

and each plate having a vertical rear edge with an L flange for seating interengagement with the respective recessed side of the casing jamb and having its outer edge inclined to suit the incline of the window sash when in predetermined open position, means attached to the rear side of the window sash near each side edge thereof for detachable sliding interengagement with the respective plates, and means attaching each plate to the casing.
